PHOTOGRAPHIC FLASH GUN OR SIMILAR ARTICLE

James M. Conner, Glendale, Calif., Allan C. Curtiss, Cambridge, Mass., and Henry Dreyfuss, South Pasadena, Calif., assignors to Polaroid Corporation, Cambridge, Mass., a corporation of Delaware

Filed Oct. 2, 1963, Ser. No. 76,825

Term of patent 14 years

(C. D61—1)

FIGURE 1 is a side elevational view of a photographic flash gun or similar article, showing our new design;

FIG. 2 is a rear elevational view thereof;

FIG. 3 is an elevational view of the side opposite that shown in FIGURE 1;

FIG. 4 is a front elevational view thereof;

FIG. 5 is a top plan view thereof; and

FIG. 6 is a bottom plan view thereof.

The flash plug cord is shown partially broken away to indicate variable length.

We claim:

The ornamental design for photographic flash gun or similar article, substantially as shown and described.
